UNITED STATES PATENT OFFICE

2,550,565

DENTAL FOUNTAIN CLEANER

Charles L. Hyser, Bronxville, N. Y., assignor to
Orajet Corporation, Wilmington, Del., a corpora-
tion of Delaware

Application September 17, 1948, Serial No. 49,711

7 Claims. (Cl. 128—229)

1

The present invention relates to dental fountain cleaners in which are provided a perforated hollow head communicating with hollow handle structure for connection to a supply of washing liquid under pressure, and, more particularly, to a type thereof adapted for housing in the handle a supply of dentifrice solids, the present invention constituting an improvement on that disclosed in my abandoned application Serial No. 34,026, filed June 19, 1948.

A general object of the present invention is to provide such a structure in a simplified, highly efficient and sanitary form which is readily and economically manufactured in mass production, which will accomplish effective cleaning without brush-bristle scrubbing that may irritate tender gums, and which features removable parts including jet forming structure and dentifrice material holding means to permit ready and thorough cleaning.

A more specific object of the present invention is to provide such a dental fountain cleaner characterized by a particular type of hollow head structure wherein jet outlets are formed in a removable wall-forming body closing off one side of said hollow head structure so as efficiently to permit removal for cleaning both the interior of the hollow head and the outlets.

Another object of the present invention is to provide such apparatus in a form whereby hollow handle structure thereof constitutes a receiving shell in which removable partition means is located to provide a pocket for holding dentifrice material with the mouth of the pocket located in the path of supplied washing liquid, outlet from the pocket to a passage downstream thereof leading to jet head structure being in the vicinity of the mouth of the pocket to assure swirl of supplied liquid into the pocket to pick up and admix therewith an amount of the dentifrice in an effective manner.

Another object of the present invention is to provide structural embodiments of the device which are readily constructed and permit efficient use and operation thereof.

Other objects of the invention will in part be obvious and will in part appear hereinafter.

The invention accordingly comprises the features of construction, combination of elements and arrangement of parts, which will be exemplified in the construction hereinafter set forth, and the scope of the invention will be indicated in the claims.

For a fuller understanding of the nature and objects of the invention, reference should be had

2

to the following detailed description taken in connection with the accompanying drawing, in which:

Fig. 1 is a side elevational view of a complete dental jet cleaner device showing in perspective the manual cleaner apparatus unit thereof which embodies the present invention, parts being broken away and spigot structure to which the device may be attached for use being indicated in dotted lines as is one position of an anchorage manipulator;

Fig. 2 is an enlarged plan view, with parts broken away, of the head end of the manual apparatus unit shown in Fig. 1;

Fig. 3 is an enlarged longitudinal section, with parts broken away, of head and handle structure shown in Fig. 1, being taken substantially on line 3—3 thereof;

Fig. 4 is a perspective view of the partitioning strip element shown in Fig. 3;

Figs. 5 and 6 are sectional views taken respectively on lines 5—5 and 6—6 of Fig. 3;

Fig. 7 is a perspective view of a tool adapted for withdrawal of the partitioning strip shown in Figs. 3 and 4 from the hollow handle;

Fig. 8 is a view similar to Fig. 2, but to a larger scale, of a modified form of head structure of the present invention; and

Fig. 9 is a sectional view taken substantially on line 9—9 of Fig. 8.

Referring to the drawing, like numerals identify similar parts throughout and, as will be seen from Figs. 1 to 6 inclusive, an embodiment of the present invention may comprise a head structure 10, a handle structure 11, supply hose means 12, and a hose anchoring device 13.

As best seen in Figs. 1, 2 and 3, the head structure 10 comprises hollow body 14 having a chamber 15 therein defined on one side by a wall-forming body 16, preferably in the form of a cylindrical button-like element and which may be formed as the head of a screw 17 threadably anchored in an internally threaded socket 18 in the bottom of the chamber 15, as best shown in Fig. 3. A plurality of jet outlets or openings are provided in the head structure 10, preferably by forming a plurality of grooves 19—19 in the cylindrical surface of the screw head 16.

The head structure 10 is mounted on an end 50 of handle structure 11, which is preferably constructed in the form of a hollow shell 20 having a bore 21 extending therethrough communicating at its downstream or outlet end 22 with the chamber 15. The bore 21 is provided with a counterbore 23 which provides an annular shoulder at

its inner end 24. The outer or upstream end 25 of counterbore 23 is internally threaded, as best shown in Fig. 3, threadably to receive an externally threaded nipple connector 26 on one end of the water supply hose 12. Preferably the outer end of handle structure 11 is externally knurled at 27, as is the nipple connector 26, as best shown in Fig. 1, so that cooperatively they provide a convenient hand grasp for secure engagement by the fingers of the user.

The upstream end of supply hose 12 is fitted with suitable anchorage or connecting means 13 for ready mounting to a water supply spigot. Preferably this anchorage structure comprises an externally threaded nipple 28 which is loosely received within an expansible sleeve 29, preferably of resilient material such as rubber, held thereon by a nut 30 which forms a fixed abutment on the outer side of resilient sleeve 29. The nipple 28 is mounted upon hollow sleeve 31 in which the upstream end of the hose 12 is anchored, and an apertured cap 32 is reciprocably mounted thereon to bear against the downstream end of resilient sleeve 29. A camming lever 33 is pivoted at 34 to the sleeve 31 so that when it is flipped down from the dotted line position to the full line position shown in Fig. 1, its nose 35 cams the cap 32 upwardly to foreshorten the resilient sleeve 29 and expand it radially, as shown, for secure anchorage within the end of a spigot diagrammatically indicated by dotted lines at 36. Such anchorage structure is more fully disclosed and is defined in the claims of my copending application Ser. No. 110,730, filed August 17, 1949, for "House Attachments for Faucet Outlets and the Like."

The embodiment of the dental jet cleaner shown in the drawing is provided with means for housing a quantity of dentifrice material. This is accomplished by sub-dividing the chamber 23 into two longitudinally-extending compartments 36 and 37. Preferably this is accomplished by an elongated partitioning strip 38 of relatively rigid material, such as metal, having its inner or downstream end turned laterally to provide a flange 39, preferably shaped substantially semi-circular so that its edge closely conforms to the curvature of the inner wall of the counterbore chamber 23 and seats against annular shoulder 24. The other end of the partitioning strip 38 is turned laterally in the opposite direction to provide a similar flange 40 which is also so shaped as to conform substantially to the curvature of the inner wall of counterbore chamber 23. As a result, the partitioning strip 38 not only divides counterbore chamber 23 into the two longitudinally-extending compartments 36 and 37, but closes off the former at its downstream end while leaving its upstream end at 41 open. Conversely, the other compartment 37 is left open to communication with the outlet bore 21 at the shoulder 24 and is closed off at its upstream end by flange 40.

Communication between compartments 36 and 37 is brought about preferably by means of a hole 42 in the outer end of the flat major portion 43 of the partitioning strip 38 in the vicinity of the outer end wall flange 40. Of course, it will be understood that other means may be employed for bringing about communication between compartments 36 and 37, such as notches in the side edges of the major portion 43 of the strip 38, or by an annular groove in the inner wall of the counterbore chamber 23 in the vicinity of end wall flange 40, but it is preferred to use the hole 42 for that purpose since it may also serve for ready engagement by a withdrawing tool, as is more fully explained hereinafter.

In operation of the embodiment of the invention shown in Figs. 1 to 6 inclusive, the handle structure 11 may be threadably disengaged from the nipple connector 26 and a quantity of dentifrice material, for example that commonly marketed in the form of a paste, may be deposited in compartment 36 which serves as a retaining pocket therefor. When an amount of such paste is squeezed from its containing tube into the hollow handle 11, it will pack down into the pocket provided by compartment 36 and may substantially fill the same. The handle structure 11 is then threadably re-engaged upon nipple connector 26 and the hose 12 anchored to a water spigot in the manner indicated above. When the valve of the spigot is opened, water under pressure will flow through the hose 12 into the pocket provided by compartment 36 to strike with considerable force the outer or upstream end of the body of dentifrice material therein, which, after some use, may be reduced to a quantity similar to that indicated at 44 in Fig. 3. As the water impinges against the body of dentifrice material, it gradually picks up and dissolves an amount thereof to carry it away toward the jet head structure 10. As indicated by the arrows shown in Fig. 3, the flow of water is first downstream into the pocket 36; then, after striking the body of dentifrice material, in the reverse direction back toward the mouth 41 of the pocket up to the communicating hole 42, there to pass through with dentifrice material mixed therewith into the outlet compartment 37, and, finally, from the inner end of the latter at the shoulder 24 to the supply or outlet bore 21 which feeds the liquid mixture to head chamber 15. The liquid mixture is then discharged under pressure from head chamber 15 through the jet openings provided by the notches 19-19 to produce high pressure jets of a cleansing liquid consisting of water in which is admixed a quantity of dentifrice material.

Manual manipulation of the cleaner apparatus unit comprising head structure 10 and handle structure 11, in a person's mouth accomplishes the desired cleaning in a manner which has proven to be unusually efficient. Manipulation is simple, and the results obtained are far superior to those had with the use of ordinary tooth brushes, while avoiding any tendency to injure tender gums, as frequently occurs in vigorous scrubbing of bristles against the gums. Further, particles which lodge under the free margins of the gums, between closely juxtaposed teeth and around and behind bridge and brace structure frequently cannot be dislodged by brushing but, as has been found, can be easily washed out by the high jet action of the apparatus of the present invention.

The embodiment of the present invention disclosed above is particularly adapted to ready cleansing of parts thereof. For example, the wall-forming button 16 in head structure 10, when in the form of the head of a screw 17, as indicated, may be readily removed by unscrewing with a simple tool, such as a screw driver. This permits access to the chamber 15 for purposes of cleansing and also permits removal of lodged material, such as dentifrice paste, that may collect in the jet grooves 19-19, by means of a brush or the like. Cleansing of the interior of the hollow handle or shell 20 is permitted by removal of the partitioning strip 38. This can

readily be accomplished with the use of a suitable tool, such as that illustrated in Fig. 7. Such tool may comprise a hook 45 having an elongated shank 46, a laterally turned end 47, and a handle 48. As shown in Fig. 3 in dotted lines, the tool hook 45 may be inserted into the open upstream end 41 of compartment 36 and its laterally turned end 47 engaged in the hole 42 in partitioning strip 38. The latter may then be readily withdrawn by a pull on the tool so that the interior of the chamber 23 may be cleansed by brushing and the partitioning strip 38 also may be freed of any solids, such as dentifrice paste, that may cake or lodge thereon.

As shown in Figs. 8 and 9, the head structure of the dental jet cleaner of the present invention may, if desired, be in the form of a cylindrical head 14, fixed on handle structure 11, and having a circular hole 115 extending transversely therethrough with which supply bore 21 communicates. The wall-forming body may be provided as a grooved end 116 of a spool or core body 49 which may be press-fitted into the transverse hole 115 for ready removal when pressure is applied thereto by the finger or any rod-like instrument. As will be seen from Figs. 8 and 9, the grooved end 116 closes off one end of the transverse hole 115 except for the jet outlets provided by the grooves 19-19, and the other end 50 of said spool closes off the other end of said transverse hole so as to form therebetween an annular chamber 51 about spool shank 52 with said chamber in communication with the supply bore or passage 21. In operation of the embodiment shown in Figs. 8 and 9, cleansing action obtainable with the use of the head structure of the embodiment shown in Figs. 1, 2 and 3 will be similarly attained.

It will thus be seen that the objects set forth above among those made apparent from the preceding description are efficiently attained and, since certain changes may be made in the above construction and different embodiments of the invention could be made without departing from the scope thereof, it is intended that all matter contained in the above description or shown in the accompanying drawing shall be interpreted as illustrative and not in a limiting sense, but any change to be effected must fall within the purview of the claims in this application.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A dental jet cleaner comprising, in combination, a hollow head having a supply passage communicating at one end with a chamber provided in the head, a removable body forming a closing side wall of the chamber and a part of one side of the head with a plurality of jet outlets for that side of the head formed substantially transversely in said wall-forming body to provide for jets that will project from that side, a hollow elongated manual handle structure supporting said head and extending away from the latter at a substantial angle to the general direction of said jet outlets, the interior of said hollow handle communicating at one end with the supply passage and having upstream thereof a chamber for reception of dentifrice material

to be gradually dissolved in passing washing liquid, and hose means connected to the other end of said hollow handle structure for supply to the dentifrice chamber of washing liquid under pressure.

5 2. In a dental jet cleaner a hollow handle construction comprising, in combination, an elongated hand grasp having an axial bore extending therethrough to provide a through water passage having an outlet end and an inlet end, the latter being provided with a counterbore to form a chamber and an annular shoulder at the inner end thereof, and an elongated partitioning strip removably positioned in the chamber with its inner end turned laterally as a substantially semicircular flange seating against said shoulder to provide a pair of elongated adjacent compartments with one substantially closed at its lower end by said flange to form a dentifrice material pocket, the other end of said strip being turned laterally at its opposite end as an outer substantially similarly shaped flange to close off substantially the upper end of the other compartment with the latter in communication with the bore at said shoulder, said strip and chamber structure providing communication between the two compartments in the vicinity of said outer flange and a passage from the dentifrice material pocket to the outlet end of the bore.

3. The dental jet cleaner structure as defined in claim 2 characterized in that provision of the communication between the compartments is by means of a hole in the strip near the outer flange which hole also serves for engagement by a withdrawing tool.

4. A liquid jet device comprising, in combination; a hollow head having a chamber therein, a circular hole in a wall thereof and a supply passage communicating at one end with said chamber; a removable button received within the hole for substantially closing it with the circumferential edge of said button being provided with a plurality of axially-extending notches to form jet outlets; a hollow elongated manual handle having one end supporting said head with its interior at that end communicating with said supply passage, said handle having upstream of said supply passage a storage chamber for reception of a supply of solids to be gradually dissolved in and admixed with liquid passing therethrough; and hose means connected to the other end of said hollow handle for supply of liquid under pressure to said storage chamber.

5. In a dental jet cleaner structure the provision of a hollow handle having a dentifrice chamber therein in the form of one of a pair of adjacent elongated compartments formed by dividing the space in the handle longitudinally by removable partitioning means, the compartment serving as a dentifrice chamber being substantially closed at its downstream end when conditioned for delivery of dentifrice-treated liquid and open only at its upstream end for reception of a body of dentifrice material, the other compartment communicating at its downstream end with a supply passage and with the upstream end of said dentifrice compartment in the vicinity of the upstream end of said partitioning means to provide an outlet passage means for said dentifrice compartment leading from the latter in the vicinity of its inlet.

6. The dental jet cleaner structure defined in claim 5 characterized by the provision of the space in said handle with a downstream end wall

through which the supply passage extends and said partitioning means therein as a removable elongated partitioning strip having its downstream end turned laterally to seat against said end wall and its upstream end turned laterally in the opposite direction to form an upstream end wall with said strip dividing the space in said handle into said pair of adjacent longitudinally-extending compartments and with the latter communicating in the vicinity of said upstream end wall.

7. The dental jet cleaner structure as defined in claim 6 characterized by the supply passage and the space which includes said dentifrice chamber being respectively in the forms of a bore and counterbore with the annular shoulder formed at their juncture serving as the downstream end wall of said space in said handle against which the laterally-turned downstream strip end seats, the latter being shaped substantially semicircular, the laterally-turned upstream

5 strip end being similarly shaped with the longitudinally-extending portion of the strip near the upstream end thereof being apertured to provide communication between the compartments and a tool-engaging hole for withdrawal of said strip.
